UNITED STATES PATENT OFFICE.

RICHARD F. PIATT, OF LOUISVILLE, KENTUCKY.

INTERNAL-COMBUSTION ENGINE.

1,299,774.

Specification of Letters Patent.

Patented Apr. 8, 1919.

Application filed March 3, 1916. Serial No. 81,874.

To all whom it may concern:

Be it known that I, RICHARD F. PIATT, a citizen of the United States, residing at Louisville, in the county of Jefferson, State 5 of Kentucky, have invented a new and useful Improvement in Internal-Combustion Engines, which improvement is fully set forth in the following specification and the accompanying drawings.

10 My invention relates particularly to that type of internal combustion engines used for the propulsion of automobiles and motor cars, although it may be applied to engines for other uses.

15 It is the object of my invention to provide a self igniting, internal combustion engine, having a secondary or driven shaft that shall be propelled by the engine at lower rotative speeds than the crank shaft of 20 the engine, without material loss of the power of the engine; also to utilize the heat contained in the burned gases exhausted from the engine to increase the power of the engine.

25 In the accompanying drawings, Figure 1 is a vertical, longitudinal sectional view of a vertical two cylinder, two-stroke cycle, gasolene or oil engine, showing the self igniting device, the manner in which the secondary shaft is propelled by the crank shaft, and the manner in which the heat in the 30 exhaust gases is utilized to add to the power of the engine.

Fig. 2 shows a vertical, transverse, sectional view of the same engine.

Fig. 3 shows a vertical transverse, sectional view of a vertical, four-stroke, cycle engine illustrating the application of my invention to that type of engine.

40 In the drawings, Figs. 1 and 2, represent a vertical, multiple cylinder, two-stroke cycle, gasolene or oil engine, having combustion cylinders, pistons, connecting rods, air admission valves, by-pass ports, exhaust ports 45 and crank shaft.

In Fig. 2, S X and Y represent an elevation of a piston having three diameters working slidably in cylinders T f and d. Cylinder T is the igniting cylinder, f the 50 combustion cylinder and d, an annular space surrounding piston X, an air motor cylinder.

The pistons of the engine are connected to the crank shaft by suitable connecting rods.

55 In Fig. 1 the small ports P in the head of the combustion cylinder, connect that

cylinder with the igniting cylinder T, about the middle of the length of the latter.

The lengthwise and cross port R, in piston S, corresponds with ports P when the piston 60 is near the end of its compressing stroke.

The openings g into combustion cylinders f, are for the purpose of allowing gasolene or oil to be sprayed into the combustion cylinders at the proper time to form the 65 working gas. I propose to spray the gasolene or oil into the combustion cylinders by means of a pump which I do not show in the drawings, as it will be the subject of an application to be made by me for a separate 70 patent.

In Fig. 1, O is an air compressor having two or more cylinders. The cylinders and crank case of this compressor are attached to the engine crank shaft and revolve with 75 it. W is the driven shaft and forms the crank shaft of the compressor which is provided with pistons i and connecting rods J, also inlet valves K in the heads of the cylinders and discharge valves I in the heads of 80 the pistons, so that air compressed in the cylinders is discharged into the crank case and passes through the hollow fixed bearing N, in which the driven shaft W works, to the pipe K which conducts the air to the heater. 85

D is an air heater containing the coil E for the purpose of heating the air compressed in the air compressor O, by means of the burned gases exhausted from the engine cylinders.

C is a check valve which prevents air in pipe n from passing to the coil E, but allows air in E to pass to n.

A is an air reservoir for the purpose of storing compressed air. B is a stop cock for 95 the purpose of retaining the air in A.

F is a four-way cock for the purpose of controlling the air from the air compressor O, or from the air reservoir A, as it passes to the air motor.

J is a stop cock which opens pipe K to the atmosphere.

M is the exhaust port for the combustion cylinders and is connected to heater D by the pipe L.

G is a pipe leading from heater D to convey the exhaust gases to the atmosphere, or to an exhaust muffler.

H is a pipe to convey air from the four-way cock F to the atmosphere, or to an exhaust muffler.

Pipes I, I² connect the four-way cock F

with the rotating air valves U U^2 of cylinders d . The cylinders d , together with the hollow rotating valves U U^2 and the pistons Y form an air motor for the purpose of utilizing the power in the air compressed in the air compressor O , and heated and expanded in the heater D , to assist in turning the engine crank shaft.

The hollow rotating valves U U^2 are air inlet and exhaust valves for the air motor cylinders d , and have parts arranged to cut off the air admission before the end of the working stroke, and are driven by a chain V from the engine crank shaft, by means of sprocket wheels on the valve shafts and the crank shaft. The air motor may be started and run in either direction by admitting air to the motor, either through U for one direction of rotation, or through U^2 for the opposite direction.

Fig. 3 represents the application of my invention to the four-stroke, cycle type of internal combustion engine. In this type of engine, the small piston S and the small cylinder T , are the same as in the two-stroke cycle, but the cylinders of the air motor h are formed by making the lower portion of the pistons e smaller than the middle portions a , and causing the portions e to work in cylinders Z , which are smaller in diameter than the engine cylinders.

The rotating air valves U U^2 are used for the air admission and exhaust to the air motor in a manner similar to that in which they are described above as being used in the two-stroke cycle type of engine.

The operation of my invention is as follows:—

When it is desired to start the engine, the air reservoir having been previously charged with air at considerable pressure, the four-way cock F is set for the direction of rotation desired and air admitted to the air motor by opening stop cock B sufficiently long to start the engine rotating. Rotation of the engine having commenced, air is drawn into the crank case chambers through the air inlet valves as the pistons rise. When the pistons descend, the air is forced through the by-pass ports into the combustion cylinders, clearing out the burned gases through the exhaust ports and supplying fresh air for compression in the combustion cylinders of the engine. When a piston closes the inlet and exhaust ports of a combustion cylinder f , compression of the air commences in the cylinder and gasoline or oil is sprayed into the cylinder through the opening g by a pump previously mentioned in this specification, forming an explosive gas. As the piston nears the upper end of its stroke, and the gas is compressed to a considerable pressure, a small portion of the compressed gas contained in the combustion cylinder f enters

the small igniting cylinder T and is further

compressed by the small piston S to a pressure sufficiently high to cause the gas to ignite from the heat due to compression.

It will be noted by reference to the drawings that when the piston S has traveled about half way up into cylinder T , the cross port R is closed by the cylinder walls of T and the small ports P are closed by the piston S , thus confining the air in the upper part of igniting cylinder T until the piston S reaches the end of its stroke, when the cross port R registers with the ports P allowing the gas in the igniting cylinder T , which has been ignited by the high compression occurring in that cylinder, to flow into and ignite the gas in the combustion space of the combustion cylinder f , thus producing a working stroke of the engine. The cross port R and the registering ports P cause the flame incident to ignition of the highly compressed gas or mixture, to pass into the combustion cylinder at somewhat widely separated points, so that ignition takes place on opposite sides of the cylinder axis, and ignition and explosion of the mixture are hence made uniform over the piston area, a result which in practice it is found desirable to attain. The engine having been started, as described above, the cylinders of air compressor O , being attached to the engine crank shaft, revolve with the crank shaft while the pistons of the compressor, being attached to the driven shaft W , reciprocate in the cylinders as shaft W is required to do work and does not readily revolve.

The reciprocating of the pistons of the compressor causes the compressor to draw in air through its inlet valves and discharge the air into its crank case, from whence it flows through the pipes provided through the air heater D to the air motor previously described. The cubical contents of the air compressor cylinders being considerably greater than the cubical contents of the air motor cylinders, and the air being cut off from the air motor cylinders early in the stroke of the motor, and the volume of the air compressed being largely increased by being heated to a high temperature in the heater, causes a considerable air pressure to accumulate, which, when increased sufficiently, will cause the driven shaft W to revolve at a lower speed than the crank shaft.

The relation between the speed of the crank shaft and that of the driven shaft depends upon the work to be performed by the driven shaft; the greater the effort required to turn the shaft, the lower will be its speed as related to the speed of the crank shaft.

When it is desired to operate the engine without turning the driven shaft W , the stop cock J is opened and the air compressed in the air compressor allowed to discharge into the atmosphere.

When it is desired to charge the air reser-

voir with compressed air, the stop cock B is opened while the engine is driving the driven shaft W.

In the arrangement of the air compressor 5 and air motor, which I have provided for causing the driven shaft to revolve at a lower speed than the engine crank shaft, the air compressed in the air compressor, due to the difference in rotative speeds of the crank 10 shaft and driven shaft, is utilized in the air motor to assist the engine in doing work.

I arrange the ports in the valves of the air motor so that the admission valves close 15 early in the stroke of the pistons, thus utilizing the air expansively and in the most economical manner; but as is well known in the art, it is not possible to so construct an air motor that it will develop and deliver as much power as was required to compress the 20 air which supplies it.

Under some conditions of operation the losses occurring, were only the compressor and air motor used for the purpose intended, would be of such magnitude as to seriously 25 interfere with the usefulness of the system.

To obviate the losses which occur, and to add to the power available for propelling the driven shaft, I employ the heater D and heat the air compressed to a very high temperature 30 by means of the heat contained in the exhaust gases from the engine before using the air in the motor, thus very largely increasing the volume of the air available for driving the motor and adding to the power it develops.

In practice there will ordinarily be employed a plurality of cylinders with their pistons, connecting rods, cranks, and other co-acting elements, though the invention 40 may be embodied in an engine employing but one explosion cylinder and piston with the necessary coöperating parts. It is hence to be understood that where in the claims a cylinder or piston is recited in the 45 singular number, it is not intended to exclude, but rather to include, a plurality of cylinders and pistons. In other words, as it is impossible to use a plurality without of necessity using one, the singular form is employed to cover and protect the use of one or 50 more as may be found expedient in any given case.

The air compressor here shown and described is illustrative only, and may be replaced by another of any suitable type. The air motor element may, when operated by the internal combustion element, or in the case of an automobile, when operated by the turning of the engine crank-shaft through 55 coasting and without power, act as an air compressor to store air in the reservoir.

Having described my invention, what I claim as new and desire to secure by Letters Patent, is as follows:

60 1. An internal combustion engine com-

prising, in combination, an explosion cylinder, piston, connecting rod, and crank-shaft; a power-transmitting shaft distinct from the engine crank-shaft; an air compressor interposed between the engine crank-shaft and 70 the power-transmitting shaft, and itself provided with a crank-pin; a revolving casing attached to one of said shafts and provided with cylinders; pistons movable within said cylinders; connecting rods connecting said 75 pistons with the crank-pin of the other of said shafts; an air motor connected with and serving to turn or aid in turning the engine crank-shaft; and an air pipe communicating with the cylinders of the air compressor, and serving to deliver air therefrom to the air motor.

2. An internal combustion engine comprising, in combination, a cylinder having two axially alined portions of differing internal diameter; a piston having two portions of correspondingly differing diameter to fit and move axially within said cylinder, one section of said cylinder together with its piston constituting an explosive engine 85 element, and the other section of said cylinder and its piston constituting an air motor element; a crank-shaft connected with and turned by said elements; a power-transmitting shaft distinct from said crank-shaft; an 90 air compressor interposed between and connecting said two shafts; and a connection between the compressor and the air motor element; whereby air compressed by the compressor is delivered to and caused to actuate the air motor element.

3. A self-starting internal combustion engine comprising, in combination, an internal combustion cylinder and an air cylinder; pistons working in said cylinders; a crank-shaft; a connecting rod connecting said pistons and crank-shaft; a power-transmitting shaft distinct from the engine crank-shaft; an air compressor interposed between said 105 shafts and serving to transmit motion from one to the other; an air reservoir; a pipe connecting said air reservoir with the air compressor; a pipe connecting the air reservoir with the air cylinder; a heater encompassing a portion of the air pipe connecting 110 the reservoir and the air compressor; and a pipe leading from the exhaust of the engine to the interior of said heater to supply heat thereto.

4. An internal combustion engine comprising, in combination, an internal combustion cylinder and an air cylinder; pistons working in said cylinders; a crank-shaft; a connecting rod connecting said pistons and crank-shaft; a power-transmitting shaft distinct from the engine crank-shaft; an air compressor interposed between said shafts and serving to transmit motion from one to the other; a pipe connecting the air compressor with the air cylinder; a heater serv- 120 125 130

ing to heat the air during its passage from the air compressor; and a pipe leading from the exhaust of the internal combustion engine to said heater to supply heat thereto.

5. The combination with an internal combustion engine, a secondary or driven shaft, an air compressor connected to the engine crank shaft and the driven shaft, an air heater and an air motor, for the purpose of propelling the driven shaft at lower rotative speeds than that of the engine crank shaft, of an air reservoir for the purpose of storing air for starting the engine, and means for charging the air reservoir with air at high pressure, either by the air compressor, or by the air motor working as an air compressor.
10. The combination with an internal combustion engine, a secondary or driven shaft,
15. pressure, either by the air compressor, or by the air motor working as an air compressor.

6. The combination with an internal combustion engine, a secondary or driven shaft,

an air compressor connected to the engine crank shaft and the driven shaft, an air heater, an air motor and an air reservoir for the purpose of starting the engine and propelling the driven shaft at lower rotative speeds than that of the engine crank shaft, of a four-way cock connected by suitable pipe connections between the air compressor, the air motor and the air reservoir, for the purpose of starting and operating the air motor in either direction.

In testimony of which invention I have 30 hereunto set my hand.

RICHARD F. PIATT.
